FIG. 5.

Inventor
Michael Karmann

By *Wm. S. Hodges* Attorney

UNITED STATES PATENT OFFICE.

MICHAEL KARmann, OF HIGHLAND PARK, MICHIGAN.

ARTIFICIAL TOOTH.

Application filed May 26, 1922. Serial No. 563,875.

To all whom it may concern:

Be it known that I, MICHAEL KARmann, a citizen of the United States, residing at Highland Park, in the county of Wayne 5 and State of Michigan, have invented a new and useful Artificial Tooth, of which the following is a specification.

This invention is an artificial tooth of the type employed in dental bridge work.

10 One of the objects of the invention is to provide an artificial tooth, and a backing therefor, so constructed that the tooth may be removed and a new one substituted, without necessitating the removal of the bridge 15 from the mouth of the patient. A further object is to provide means for so connecting the tooth with the backing, as to prevent any relative play. A further object is to provide an artificial tooth of the character 20 mentioned, having ample thickness between the incisal edge thereof and the contiguous extremity of the tenon of the backing, whereby a tooth of maximum strength is provided. A further object is to provide 25 ample thickness of the wall of the tooth, between the tenon and the front or exposed face thereof, to permit grinding of the tooth in special cases, and to insure sufficient opaqueness to prevent the tenon from showing 30 through when the tooth is in position.

The invention will be hereinafter fully set forth and particularly pointed out in the claims.

In the accompanying drawing:—

35 Figure 1 is a longitudinal sectional view, illustrating an artificial tooth constructed in accordance with the invention, the tooth being attached to the backing. Figure 2 is a rear view thereof. Figure 3 is a bottom 40 view thereof. Figure 4 is a rear view of the tooth detached. Figure 5 is a front view of the backing detached.

Referring to the drawing, 10 designates a backing which may be made of any suitable 45 material, such as gold or one of the metal alloys well-known in the trade. Said backing is preferably of flat or plate-like form constructed of one piece of metal, thereby eliminating seams and joints, and preventing 50 the danger of solder getting to the front of the backing post. Extending from the front face of the backing 10 is the tenon or post 11, having its base 12, projecting beyond the plane of the base edge of the backing 10, and beveled as shown in the drawing. Said post tapers from the base toward

the other or incisal end, and is provided with overhanging longitudinal shoulders 13, and an overhanging shoulder 14 on the narrow end. The projection portion 12 of the base 60 of the post or tenon 11 is of advantage in special cases, where the said projection, covered with solder after the construction 65 of the bridge, may fit into a socket of recent extraction, thus adding strength to the bridge and being more sanitary than present day practice.

The tooth 15, which will be of proper shape conforming to its location in the mouth of the patient, is provided with the 70 usual incisal edge 16, and an inclined base 17. The rear wall of the tooth is provided with a dove-tailed groove 18, having overhanging longitudinal and end shoulders, complementary to the shoulders 13 and 14 of 75 the post 11.

In practice, the tooth is engaged with the backing plate, by placing the base end of the groove 18 in register with the narrow end of the post or tenon 11, and moving the 80 tooth toward the base. In this manner the tapered post with the overhanging shoulders 13 and 14, engage the correspondingly tapered walls of the groove 18, making the tooth fit snugly to the backing, so that it 85 will be firmly retained in place without play and yet be capable of ready removal as occasion may warrant. It will be noted that the projecting portion 12 of the tenon 11 extends beyond the plane of the inclined 90 base 17.

The advantages of the invention will be readily apparent to those skilled in the art. By constructing the backing of one integral piece of material, it is prevented from drawing 95 when fire is applied, and the result is that the backing retains the same shape as before the application of heat. The same backing, including the dove-tailed tapered post or tenon, may be used for the twenty- 100 eight different styles of teeth. By providing a maximum thickness between the incisal end of the tooth and the contiguous end of the groove 18, a tooth of ample strength is provided, and by constructing the front wall 105 of the tooth of maximum thickness between the tenon and the front exposed face, an ample thickness is provided to permit of grinding of the tooth in special cases, and yet the tooth will be sufficiently opaque to 110 prevent the tenon from showing through.

Having thus explained the nature of the

invention and described an operative manner of constructing and using the same, although without attempting to set forth all of the forms in which it may be made, or all 5 of the forms of its use, what is claimed is:

1. The combination with an artificial tooth having a plane back face with a groove therein and a beveled base intersecting said back face, of a plate-like backing 10 plate covering the back face of the tooth and having a tenon on its front face complementary to said groove, the base end of said tenon projecting beyond the plane of the base edge of said plate and also beyond the plane of the beveled base of the tooth, 15 the base end of said tenon being beveled, the tooth being of substantial thickness between the incisal edge and the contiguous end of the groove, whereby ample thickness is provided to permit grinding of the tooth and yet retain sufficient 20 opaqueness to prevent the tenon from showing through.
2. The combination with an artificial tooth having a plane back face with groove 25 therein and a beveled base intersecting said

back face, of a plate-like backing plate 20 covering the back face of the tooth and having a tenon on its front face complementary to said groove, the base end of said tenon projecting beyond the plane of the base edge of said plate and also beyond the plane of the beveled base of the tooth, 25 the base end of said tenon being beveled, the tooth being of substantial thickness between the incisal edge and the contiguous end of the groove, whereby ample thickness is provided to permit grinding 30 of the tooth and yet retain sufficient opaqueness to prevent the tenon from showing through.

In testimony whereof I have hereunto set my hand.

MICHAEL KARMANN.
